METHOD OF MAKING HEAT EXCHANGER
FINS

Floyd J. Sibley, Detroit, Mich.

Application January 19, 1939, Serial No. 251,665

6 Claims. (Cl. 29—157.3)

My invention relates to an improved heat exchanger fin and a method for making and for applying the same. My improved heat exchanger fin is disclosed and claimed in my divisional patent application Serial No. 277,213 filed June 3, 1939.

It is an object of my invention to provide an improved heat exchanger fin having superior thermal conductive characteristics and comprising a heat conductive metal vane, a heat conductive metal base flange, and the vane and the base flange being joined integrally through a junction which is thicker than either the base flange or the vane extending therefrom.

It is also an object of my invention to provide such a heat conductive fin in which the vane and the base flange of the fin taper thinner extending away from the thick junction in angular relation whereby the maximum amount of metal in a cross section of the fin is provided in the junction where it is useful for improving both the mechanical strength and the heat conductive properties to the fin, and metal is saved where it is not required.

It is a further object of my invention to provide such a heat exchanger fin wherein the vane extending from the base is serrated to provide a plurality of vanes integral with the base flange and presenting an increased air contacting surface as the vanes are separated by applying the base flange in close contacting engagement on a tube or other curved surface.

Another object of my invention is to provide a method for making my improved heat exchanger fin from an elongated element or bar of suitably ductile metal which consists in simultaneously cutting and thrusting the metal from one side of the element to form a raised flange on one face thereof, and shaving the deformed face of the element to detach from the element the raised flange with sufficient metal to form a heat conductive vane extending integrally therefrom.

A further object of my invention is to provide for making my serrated heat exchanger fin in accordance with the above method, and the deformed or flanged face of the ductile metal element being cut or chiselled at regular intervals before the operation of shaving the fin from the deformed face of the element or bar.

It is also an object of my invention to provide a method for simultaneously making a serrated heat exchanger fin and a finned tube construction in which the base flange of the fin is simultaneously wound tightly around a tube to be finned with sufficient tension to secure it tightly on the

tube while aiding in the operation of drawing the shaved fin from the bar.

The invention itself, however, both as to the shape and construction of my heat exchanger fin and as to the method of making and applying the fin, together with additional objects and advantages thereof, will best be understood from the following description when read in conjunction with the drawings, in which:

Fig. 1 is a plan view showing one form and arrangement of means suitable for making my heat exchanger fin from a bar of metal;

Figs. 2 and 3 are side elevational and end elevational views thereof respectively;

Fig. 4 is a cross sectional view of a tube showing how the serrated fin is applied thereon;

Fig. 5 is a longitudinal sectional view of a finned tube showing the improved heat exchanger fin installed;

Fig. 6 is a cross sectional view of the heat exchanger fin, per se, showing the improved conformation thereof;

Fig. 7 is a perspective view showing a portion of the elongated bar as it appears after it has been swaged to form the base flange rising from one side which has been chiselled or cut at regular intervals prior to the operation of shaving the fin from the bar, and

Fig. 8 is a plan view, partly diagrammatic showing how my apparatus may be disposed for continuously working a circular bar.

Referring more particularly to Figs. 1, 2 and 3 of the drawings, suitable means for making my improved heat exchanger fin comprises an element 1 of any suitable metal from which the fins are to be made. For this purpose a metal is selected such as copper, or aluminum or any other metal having suitable characteristics of thermal conductivity, ductility, corrosion resistance and the like according to the use for which the fins are to be used, as will be readily understood. The stock member 1, of suitable metal, is an elongated element preferably in the form of a bar of rectangular cross section, either straight or circular.

In accordance with my method of making improved heat exchanger fin, a flange 2 is formed on one face of the bar by cutting and pushing up the metal from one side. This may be accomplished by various tools sliding, or reciprocating as will be readily understood, but for this purpose I find it convenient to utilize a cylindrical thrusting roller 3 having a sharp square corner 5, shown in Fig. 3, which acts as a cutting edge. The sharp corner 5 may be other than a right

angle if desired depending upon the angular relation desired between the angularly disposed portions of the heat exchanger fin. A cylindrical guide roller 7 of smaller diameter extends down axially from the thrusting roller 3, and both are rotatably journaled on a shaft 9 supported vertically from the lower end of a bracket 11, which may be a part of a rigid cast frame 13. The frame 13 also serves to provide a suitable guide face 15 for one side of the metal bar 1 while the other side of the bar is forced against the thrusting roller 3. The lower portion of the guide frame 13 is provided with a suitable channel 15 to receive a dovetail 17 projecting from an adjustable guide 19 which is moveably mounted for slidably supporting the bottom face of the bar 1 as it passes the thrusting roller. A pair of adjusting shafts 21 are journaled at the lower ends in a pedestal flange 23 projecting from the bottom of the frame 13, and the upper ends of the shafts are threaded for adjustably entering threaded apertures 25 in the lower side of the movable guide 19. A hand wheel 27 is provided on each adjusting shaft for elevating the guide 19 as the upper face of the stock bar 1 is cut down.

As the bar 1 is moved along, a cutting or chisel roll 27 forcefully engages the upper face of the bar for cutting the metal thereof to provide transversely disposed cuts 28 at equally spaced points between the flange 2 formed by the thrusting roller 3 and the other side of the bar. For this purpose the chiselling roller 27 is provided with a plurality of chisel edges 31 which extend across the face of the roller. As shown in Fig. 3, the face of the chiselling roller 27 is slightly tapered and the chiselling edges 31 thereon are so disposed that they cut deeper into the face of the bar adjacent the flange 2 than at the opposite side. Also a tapered annular face surface 29 on the side of the chisel roller 27 serves to shape the tapered side of the flange 2 pushed by the thrusting roll 3.

The chisel roll 27 is journaled on a horizontal shaft 33 projecting from the rigid frame 13 and disposed transversely over the bar 1. As shown, the axes of rotation of the thrusting roller 3 and the chisel roll 27 lie in a plane so that the forming of the flange 2 on the bar, and the chiselling of the surface at any particular point on the upper face is performed at the same time. As will be understood, this precise arrangement is not necessary, and the chiselling roller 27 may be so disposed with reference to the thrusting roller 3 that any particular portion of the upper face of the bar is chiselled either before or after it has been swaged to form the flange 2 instead of simultaneously, and the question of the time sequence of the two operations does not arise because both operations are being performed continuously as the bar passes along. The chiselling roller 27 may also be entirely omitted when it is desired to make heat exchanger fins having vanes which are solid or unserrated as in making straight fins for mounting on a flat surface as 65 for finning the side walls of tanks and the like.

The completed heat exchanger fin 30 is shaved off from the upper face of the bar 1 after this surface has been worked to form the raised flange 2. For this operation a sharp shaver 37, 70 of suitable hardened tool steel, is secured by a bolt 39 on the upper face of the frame 13 where it is rigidly supported by suitable interlocking means, such as a pin 41, to prevent rotation. The shaver is disposed with the sharp edge 43 toward

the approaching bar 1 in a position to have the cutting edge substantially on a level with the lower edges of the chisel points 31, as shown in Figs. 2 and 3 in order to shave a cut of a proper depth. As the bar 1 is moved toward the shaver 37 the flange 2 is shaved from the upper face of the bar and sufficient joined metal is shaved from the upper face of the bar with the flange to provide a vane, or a plurality of vanes 36, extending therefrom. The shaver 37 may be clamped on a wedge or shim 44 to facilitate adjusting its position correctly, and it is suitably positioned for cutting through the bar substantially along a position represented by the dotted line 43' shown in Fig. 7.

To apply the fin on a tube 45, the tube is rotatably mounted adjacent the side of the bar and slightly inclined from vertical, as shown in Fig. 2. For this purpose the lower end of the tube 45 may be firmly gripped in any suitable chuck 47 which is firmly secured on the upper end of a threaded shaft 49. The threaded shaft 49 is supported through a threaded bracket 51 secured on the side of the frame 13 by bolts 53. The shaft 49 is rotated with suitable force to hold the fin taut and wind it firmly on the tube 45 as it is shaved from the bar 1. The ends of the fin may be secured to the tube in any suitable manner as by soldering or brazing. For rotating the shaft 49, a handle 55 may be pivotally journaled on the lower end of the shaft for driving the shaft through a pawl wheel 57 and ratchet 59, although any power driven means may be provided for this purpose as will be understood.

To force the stock bar 1 along, any suitable work feed means may be utilized such for example as feed rollers 61 and 63 journaled between brackets 65, as shown in Fig. 2. One of the rollers 61 is provided with a worm wheel 67 which is forcefully driven by a worm 69 rotated by a convenient hand wheel 71 on an extended shaft 73. The lower roller 63 is journaled in end bearing blocks 75 which slide in slots 77 in the end bracket 65, and a threaded shaft 79 extends down therefrom to a hand wheel 81 for adjusting the position of the lower roller as the bar is shaved thin. Turning the hand wheel 71 in the proper direction, the stock bar 1 may be drawn past the thrusting roller 3, the chisel roll 27, and the shaver 37 to form and separate the fin therefrom. Similarly work feeding means or rolls may be disposed at the rear for pushing the bar 1, and if desired any suitable power means may be provided for moving the bar 1 and for rotating the shaft 49 to wind the fin on the tube, as will be readily understood.

To make heat exchanger fins in accordance with my method, an upstanding flange 2 is formed or raised on the upper face of an elongated bar 1 of suitable metal. As previously explained, this may be accomplished by passing the bar 1 firmly against the sharp edge 6 of a thrusting roller 3 which cuts and thrusts the metal up from one side of the bar in an operation sometimes referred to as swaging. This may be accomplished in a series of steps if desired. Also either simultaneously, or before, or after forming the upstanding flange 2, the upper face of the bar is provided with cuts 28 extending transversely from the position of flange 2 to the other side of the bar at regular intervals. The bar then appears as shown in Fig. 7. The flanged face of the bar is then shaved off just deeply enough to remove the flange with sufficient metal from the chiselled surface of the bar to form a plurality

of heat exchanger vanes integral with the flange and extending angularly therefrom. The end of the serrated fin is attached to a tube to be finned, in any suitable manner as by soldering or brazing, and the tube is rotated with sufficient force to draw the fin taut to aid in separating it from the bar and to fix the fin firmly in helical relation on the tube, as shown in Figs. 4 and 5.

When a straight bar 1 is used, the bar is preferably reversed end-for-end each time it is passed through the rollers in order to work the upper face of the bar down equally from both sides, because the operation tends to remove more metal from one side. My method of making fin may be performed as a continuous process by providing the bar of stock material in a circular or cylindrical form, as shown in Fig. 8. This may be accomplished by taking a long straight bar 1 and bending it circular and welding together the abutting ends. In this manner the stock may be worked down into a continuous fin of great length. When the stock bar is worked continuously, two machines are preferably provided for working the bar in series relation and keeping the upper surface level by pushing up the flanges from opposite sides of the bar, as shown. Either straight or serrated heat exchanger fin may be made by omitting or performing the step of chiselling or cutting the surface of the bar at regular intervals as described.

My improved heat exchanger fin 30 comprising the base or mounting flange 2 and the heat absorbing or emitting vane or vanes 36, formed as previously described, has improved heat conducting properties and operates very efficiently to transmit heat between the base flange and the vane. As shown in Fig. 6, the shape of the fin in cross section is such that the heat emitting vane extends angularly from one edge of the base flange joining integrally therewith through a junction which is substantially thicker than either the base flange or the vane. By "angularly" is meant any angle to distinguish from parallel. As will be seen, the vane and the base flange taper thinner toward the outer edges to save metal where it is not useful. Also the shape of the fin so formed is such that the outer corner 83 of the junction is a sharp edge or corner and the inner corner is a curve 85 providing extra metal in the junction for efficient heat conduction and rigid mechanical support. The sharp outer corner 83 also makes the lower surface of the base flange 2 completely contact the surface to be finned with a close firmly abutting engagement providing a large contact area, and also bringing the heat conductive vane close to the surface which is to be finned for rigid support and efficient thermal contact on the finned surface. Furthermore, a heat exchanger fin made in accordance with my method has good solid metal which is free from checks in the junction between the base flange and the vane and this provides superior thermal conductive properties.

The above features and characteristics are very useful either when the vane 36 of the fin is undivided, as for finning flat surfaces, and also when serrated to provide a plurality of vanes 36 which are separated when the base flange is installed on a curved surface. When the serrated arrangement is provided, the large number of separated vanes 36 projecting integrally from the base flange 2, provide more efficient thermal coupling with the air, or other gas or vapor, because a greater contacting area is provided in the crevices between the vanes, and the eddying or

swirling of the air therebetween retards the circulation of the air and stirs or scrubs the air into more intimate contact with the metallic surfaces.

5 It is not my intention to limit my invention to the precise steps herein described nor to the particular means or the specific materials referred to, since these are referred to merely as the preferred arrangement in my heat exchanger fin and the method for making it. It will be understood that the present disclosure is illustrative merely, the invention comprehending all variations thereof.

I claim:

15 1. The method of making a flanged heat exchanger fin from a bar of ductile metal which consists in, setting a sharp edged tool slightly below and slanting into a part of the face of the bar and progressively cutting and thrusting to upset some metal to form a projection thereon, and shaving off the projection with sufficient metal from the surface to form a flanged fin having an integral junction thicker than either the fin or the flange and having a sharp outer corner and a rounded inner corner.

20 2. The method of making a flanged heat exchanger fin from a bar of ductile metal which consists in, setting the sharp edge of a tool slightly below and moving it into a face of the bar in a slanting approach thereto for progressively cutting and thrusting to upset the metal from one side of the bar and to form a projection on the face of the bar, and shaving off the projection with sufficient metal off of the face of the bar from the projection toward the other side of the bar to form a flanged fin having an integral junction thicker than either the flange or the fin and having a sharp outer corner and a rounded inner corner.

25 3. The method of making a heat exchanger fin from an elongated bar of ductile metal which consists in, cutting and thrusting the metal from one side of the bar to form a raised flange on one face of the bar, cutting the face of the bar at regular intervals from the flange position to the other side of the bar, and shaving the flanged face off of the bar in such a manner as to remove the flange with sufficient metal from the bar to form a plurality of vanes extending integrally therewith.

30 4. The method of making a heat exchanger fin from an elongated bar of ductile metal which consists in, cutting and thrusting the metal from one side of the bar to form a raised flange on one face of the bar, cutting the face of the bar at regular intervals from the flange position to the other side of the bar, shaving the flanged face off of the bar in such a manner as to remove the flange with sufficient metal from the bar to form a plurality of vanes extending integrally therewith.

35 5. The method of making a heat exchanger fin from an elongated bar of ductile metal in the form of a circle or cylinder for continuous operation which consists in, forming an upstanding flange on one face of the bar by swaging or cutting and pushing the metal up from one side thereof, cutting said face of the bar transversely at substantially regular intervals from the position of said flange to the other side of the bar, shaving the flanged face off of the bar in such a manner as to remove the flange therefrom with

40 45 50 55 60 65 70 75

sufficient metal to form a vane extending integrally from one edge of the flange, and performing said flange forming, chiselling and shaving operations continuously around the cylindrical bar.

6. The method of making heat exchanger fin as set forth in claim 5, except that said operations are performed continuously at two differ-

ent points around the circumference of the bar to produce two separate heat exchanger fins, and the flanges are swaged up alternately from opposite sides of the face of the bar at said two different points to keep the worked face of the bar level as it is shaved down.

FLOYD J. SIBLEY.
